UNITED STATES PATENT OFFICE.

JOHN W. PLACE, OF TUCKAHOE, NEW YORK.

FASTENER.

No. 895,454.

Specification of Letters Patent.

Patented Dec. 1, 1908.

Application filed October 2, 1907. Serial No. 395,429.

To all whom it may concern:

Be it known that I, JOHN W. PLACE, a citizen of the United States, residing in Tuckahoe, in the county of Westchester, in the State of New York, have invented a certain new and useful improvement in Fasteners, of which the following is a specification.

The invention is intended for securing strings of convenient size applied around packages. I will describe it as thus applied to a package of letters to be carried in the mails.

The material may be low steel or other metal having a moderate degree of elasticity and sufficient thickness and strength to resist the pull to which it shall be subjected. Its elasticity is not important in contributing to the holding of the string. The fastening may be cheaply made and applied with rapidity and ease. It holds for any period under all conditions. It is applied by a simple circular movement of the hand, repeated for further security as required. It is released by the reverse movements of the free end of the string.

The following is a description of what I consider the best means of carrying out the invention.

Figure 1 is a face view of the fastener, applied to a batch of letters, weakly secured by one circular movement of the hand. Fig. 2 is a corresponding view showing the fastening completely secured by the addition of a second circular movement of the hand and the consequent encircling of the crossing point of the wires at the front by a second turn of the string. Figs. 3, 4, 5, and 6 represent views of the metal portions alone, on a larger scale. Fig. 3 is a face view. Fig. 4 is a corresponding edge view. Fig. 5 is an edge view seen at right angles to the view in Fig. 4. Fig. 6 is a face view, the reverse of that shown in Fig. 3. Fig. 7 shows a modification. The permanently attached end of the wire is extended outside of the helix. The other portions of the wire are the same as before but the string is differently engaged.

Similar letters of reference indicate like parts in all the figures.

Describing the fastener as lying in a horizontal position on the upper face of the package:—A is a loop or eye formed in one end of the wire; B is an extension therefrom, horizontally; C is a descending bend or dive;

D a further extension horizontally sharply bent, (to the left in Fig. 3). From this point the wire makes two complete, and they may be exactly helical, circuits. 60

Assuming the lower portion of Figs. 3, 4 and 6, which is the working side of the device, to be the front, the portion E extends rearward, the wire continuing across at the back. I will designate by F the point where 65 the wire extends across on the back side. From thence forward, marked G, thence across the front marked H, thence again rearward, marked I, again across the back, marked J, and again forward, marked K. 70 We have now followed the wire to the end of the last, the uppermost, circuit. It is here bent shortly downward, forming a portion extending up and down through the whole depth of the fastener. This important portion of the device I will designate as a "post." 75

To use the fastener, the cord P, P' is tied in any ordinary or suitable way to the metallic fastener by the aid of the loop A and 80 allowed to extend out therefrom between the two circuits of the wire. The metal fasteners, each with a sufficient length of string, are to be kept at hand ready for application as required. 85

In applying the fastener to a parcel, the other end of the string is wound around and across the parcel in the ordinary manner indicated in Figs. 1 and 2, and the free end of the cord is inserted by a lateral movement 90 between the two circuits on either side. Assuming the motion to be from the right, the string is thus carried between the parts K and G. The operator continuing the movement causes the string to pass the eye or loop 95 A and the string is thus carried in this position around into the position shown in Fig. 1. It is then pulled with sufficient force according to the requirements of the parcel, and the string plays around the inner side of 100 the post M, until it is tightened enough, then the hand carries the free end P' of the string again around through the same course so that the string completely encircles the post M and the free portion P is again introduced 105 between the parts K and G and again caused to make a complete circuit. The hand may then be opened; the fastening is complete.

While in service the tension on the string, 110 received through the free end P' is applied directly to the midheight of the post M and

is effectually resisted. The other portions of the fastener are useful collaterally; little if any strain is received through those parts.

When it is required to undo the parcel, 5 the free end P' of the string is seized by the operator and the two circuits of the hand made in the opposite direction from the fastening direction. These movements release and remove the turns which were made with 10 the hand in applying the fastener, and leave the fastening free.

The parts N and O briefly described above 15 may be used or not, according to the purposes for which the fastener is intended to serve. The portion N which extends forward from the lower end of the post M is useful in limiting the extent to which the turns of the wire may be sprung apart. The extension upward O (shown most clearly in 20 Fig. 4) will be included in the turns of the string in completing the fastening and contributing somewhat to the usefulness. It certainly insures very completely against 25 any too wide separation of the circuits of the wire, however severely the device may be ever strained.

It will be observed that the cord $P P'$ in 30 its final position after being wound around as described encircles the front portion H of the coils and also the post M so as to have the tension of the cord received directly on the post and at the mid-height thereof. This arrangement throws none of the final holding tension on the two coils. These parts are 35 mainly of importance in guiding the cord in the act of attaching the fasteners. Their elasticity is mainly important in the act of moving the cord past the previously laid part thereof between the parts F and J at 40 the back of the fastener.

My fastener will serve with either face upward. The string may be inserted from the left side or from the right side in either position. All that is necessary is to insert 45 the string and give two rapid circular movements.

Modifications within the scope of the appended claims may be made without departing from the principle or sacrificing the advantages of the invention.

The size of the cord relatively to the width of the spaces between the turns of the wire may be varied. The best effect is obtained by using a cord of a little greater diameter 55 than the width of such spaces and allowing it to force apart the back portions F and J of the turns of the wire to attain its place.

Fig. 7 shows the part B of greater length carrying the eye or loop A outside of the 60 helical turns. This will serve about equally with the form first shown for all purposes.

This Fig. 7 also shows a modification in the manner of applying my fastener to a parcel, which may be often used with advantage whether the part B is made long or short. 65 The difference in the mode of applying my fastener in this figure lies in making the crossing of the string in the fastener instead of outside of it. In this mode the free end of the string is engaged with the fastener at 70 an earlier stage of securing the package,—so soon as it has been extended once around, shown as the longitudinal traverse. The engagement is the same as before, first slipping the free part of the string between the turns 75 of the wire on one side, shown as the left side, and drawing it to tighten. Then by another movement of the hand the string is extended from the fastener around the parcel horizontally and then again similarly engaged with the fastener by again gently 80 forcing it between the turns of the wire,—this time the place of introduction will be the further side, the top side as it lies in the drawing. After this second engagement of 85 the string with the fastener the string is drawn tight, and one more sweep of the hand is made applying the string once more between the turns of the wire and drawing tight; now the fastening by this method of 90 applying is complete. Either method is attained by a continuous movement. It is easy and rapid and requires but one hand.

I claim as my invention:

1. A fastener of wire of the character described, comprising a plurality of coils arranged helically, one end being bent parallel to the axis and then extending in an arm B radially inward, terminating in an eye A , and the other end engaged with the arm at 100 the point of departure from the coil, all substantially as herein specified.

2. A fastener of the character described, comprising two turns of a helical spring engaged together by a post formed integral 105 therewith, arranged as shown so as to transmit the strain directly from the center of such post, and allow the other portions to serve elastically as guides, and having an arm extending inward between the planes of 110 the coils and carrying an eye, in combination with a cord $P P'$ permanently attached to such eye, adapted to serve substantially as herein specified.

Signed at New York city in the county of 115 New York and State of New York this 30th day of September A. D. 1907.

JOHN W. PLACE.
